UNITED STATES PATENT OFFICE

ARMOND G. ROSSIG, OF NEW YORK, N. Y.

DESIGN FOR AN ELECTRIC CANDLE LAMP STAND

Application filed November 28, 1930. Serial No. 37,824. Term of patent 3½ years.

To all whom it may concern:

Be it known that I, ARMOND G. Rossig, a citizen of the United States, and residing in the city, county, and State of New York, have invented a new, original and ornamental Design for an Electric Candle Lamp Stand, of which the following is a specification, reference being had to the accompanying drawings, forming part thereof.

In the drawings:

Fig. 1 is a perspective view of an electric candle lamp stand showing my new design, and

Fig. 2 is a diagrammatic top plan view.

The design comprises an elongated rec-

tangular base upon which is mounted three imitation trees one at the middle and the others adjacent opposite ends of the base, the central tree being relatively larger than the end trees and being carried upon a slight annular elevation of the base, and two electric candles arranged one at each side of the central tree midway between the central tree and the end trees, the candles rising above the end trees but being of less height than the central tree.

I claim:

The ornamental design for an electric candle lamp stand, as shown and described.

ARMOND G. ROSSIG.
